R. B. CASWELL, OF PALMER, MASSACHUSETTS.

Letters Patent No. 65,723, dated June 11, 1867.

IMPROVED BLANKS FOR CALKS OF HORSE-SHOES.

The Schedule referred to in these Letters Patent and making part of the same.

TO ALL WHOM IT MAY CONCERN:

Be it known that I, R. B. CASWELL, of Palmer, Hampden county, Commonwealth of Massachusetts, have invented a new and useful Improved Process of Forming Steel for Toe-Calks of Horse-Shoes; and I do hereby declare that the following is a full and exact description thereof, reference being had to the accompanying drawings, and to the letters of reference marked thereon. In the drawings—

Figures 1 and 4 are end views of my invention.

Figure 2, a plan view of the same; and

Figure 3, a diagram of the roller used in forming the steel.

This invention consists in forming bars of steel in such shape that by merely cutting off the proper lengths toe-calks are formed ready to be welded to the shoe.

In order to accomplish this, I sink dies into an upper and lower roller A and B, which correspond in shape to the section of steel shown in figs. 1 and 4. Thus, we will suppose that the red line drawn across the centre of the figure represents the line where the circumferential faces of the rollers meet. Now this line divides the steel equally between the upper and lower rollers, and each one would have a groove sunk in it corresponding to one-half of the section of steel. These grooves are, however, of course curved so as to coincide with the circumference of the rollers. The steel when formed by these rollers consists of two long wedges joined together at their apexes, each having a number of projections, *a a a*, on one edge of their bases. These projections are formed at equal distances apart, the distances between them being the proper length of a toe-calk. They are formed by the rollers having corresponding cavities in the sides of their grooves, which leave these points upon the bars when they are rolled out, and are for the purpose of assisting the welding process by being driven into the toe of the shoe when the calk is attached. In fig. 4 is shown a form for a summer calk, which consists in making the wedge much blunter than the winter calk, but is formed substantially in the manner as the latter.

The advantages I obtain by so forming the steel are that I put the stock in the blacksmith's hands in the most convenient form for his work, whether left in bars or cut off by machinery previously. Besides this, in cutting off the calks, two calks can be cut off at one operation, saving almost half the labor of that part of the work, and the projections *a a a* upon the calks leave them in the best shape for joining to the shoe by the process of welding. Besides this, by forming the bars double in the manner shown, the same operation of rolling turns out double the amount of steel, properly formed, as would be the case if the bars were rolled singly, thus enabling the manufacturers to increase largely their productions, without increasing their expenses in proportion.

Now, having described my invention, what I claim as new, and desire to secure by Letters Patent, is—

As a new article of manufacture, bars of steel formed for toe-calks substantially in the manner herein described.

R. B. CASWELL.
